CLAIM

The ornamental design for a medical apparatus for imaging, as shown and described.

DESCRIPTION

FIG. 1 is a front elevational view of the medical apparatus for imaging of the present disclosure;
FIG. 2 is a back elevational view thereof;
FIG. 3 is a top plan view thereof;
FIG. 4 is a bottom plan view thereof;
FIG. 5 is a side elevational view of the right side thereof;
FIG. 6 is a side elevational view of the left side thereof; and,
FIG. 7 is a perspective view taken generally from the upper, front, right-hand side thereof.
The broken lines in FIG. 2 illustrate portions of the medical apparatus for imaging that form no part of the claimed design.
